US0D1080130S

(12) **United States Design Patent** (10) Patent No.: **US D1,080,130 S**
(45) Date of Patent: ** Jun. 17, 2025

(54) **COLLAPSIBLE CART WHEEL**

(71) Applicant: **Kinghood Asia Technology Development(Tianjin) Co., Ltd., Tianjin (CN)**

(72) Inventor: **Bo Peng, Tianjin (CN)**

(73) Assignee: **Kinghood Asia Technology Development(Tianjin) Co., Ltd., Tianjin (CN)**

(**) Term: **15 Years**

(21) Appl. No.: **29/842,654**

(22) Filed: **Jun. 15, 2022**

(51) LOC (15) Cl. **12-02**

(52) U.S. Cl.

USPC **D34/27**

(57) **CLAIM**

The ornamental design for a collapsible cart wheel, as shown and described.

DESCRIPTION

FIG. 1 is a front perspective view of a collapsible cart wheel, showing my new design;

FIG. 2 is a rear perspective view thereof;

FIG. 3 is a left side perspective view thereof;

FIG. 4 is a right side perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.
